(57) **CLAIM**

We claim the ornamental design for a drive housing cover, as shown and described.

DESCRIPTION

FIG. 1 is a front perspective view of a drive housing cover according to our new design;

FIG. 2 is a front view thereof;

FIG. 3 is a right side view thereof;

FIG. 4 is a left side view thereof;

FIG. 5 is a top view thereof;

FIG. 6 is a bottom view thereof; and,

FIG. 7 is a perspective view of the drive housing cover on a motorcycle.

The broken lines, which are used in FIGS. 1, 2, and 7 for the purpose of illustrating portions of the drive housing cover and also in FIG. 7 for the purpose of illustrating environment of the drive housing cover, form no part of the claimed design.

1 Claim, 5 Drawing Sheets
